UNITED STATES PATENT OFFICE.

THOMAS H. CARROLL, OF PHILADELPHIA, PENNSYLVANIA, ASSIGNOR,
BY DIRECT AND MESNE ASSIGNMENTS, TO THE CARROLL CHAIN-
LESS CYCLE COMPANY, OF NEW JERSEY.

DESIGN FOR A BICYCLE-FRAME.

SPECIFICATION forming part of Design No. 26,898, dated April 13, 1897.

Application filed December 19, 1896. Serial No. 616,348. Term of patent 14 years.

To all whom it may concern:

Be it known that I, THOMAS H. CARROLL, of Philadelphia, Pennsylvania, have invented a new and original Design in Bicycle-Frames, 5 of which the following is a specification.

My design relates to a bicycle-frame, and particularly to the shape of the back fork and brace thereof, and is illustrated in the accompanying drawings, in which—

10 Figure 1 represents a side elevation of a bicycle-frame embodying the design; Fig. 2, a vertical sectional view of the same on the line xx of Fig. 1, looking to the rear and on an enlarged scale; and Fig. 3, a perspective view of the rear of the frame.

The particular peculiarity in the shape of the frame wherein the design resides is in the back fork E, divided into two parts F and G,

lying in different vertical planes and having the piece I extending from the ends of the 20 parts F and G upward and backward to the back stay C and forming therewith and with the rear part G of the back fork a triangular shape.

Having now described my invention, what 25 I claim as new, and desire to secure by Letters Patent, is—

The design for a bicycle-frame substantially as herein shown and described.

In testimony of which invention I have 30 hereunto set my hand.

THOS. H. CARROLL.
